ELECTRICAL DRY SHAVING IMPLEMENT HAVING A HINGEABLE SHEARING SECTION

Jacob L. Kleinman, New York, N.Y.

Application April 21, 1958, Serial No. 729,928

4 Claims. (Cl. 30—43)

This invention relates to the construction of shaving implements in general, and more particularly to a type operated by a motor and known as dry shavers or electric razors.

The present type of electric shavers are constructed in such a manner wherein only one of the outer side portions of the motor shaft is connected to the actuating elements for operable purposes; this form of structure prevents even-distribution of the motor-power upon the motor shaft and causes eccentric strain upon such motor shaft thereby burdening the motor with excessive strain while operating the actuating elements for shaving purposes. Thus the present type of shaver must be provided with an extra-powerful motor of a size and structure larger than actually needed for an instrument of this kind.

Furthermore, such eccentric strain causes additional frictional rubbing of the outer shaft portion within its seat, constantly removing material therefrom, to an extent whereby such shaft becomes too loose within its seat and ceases to function; in which case the motor becomes useless.

In accordance with my invention, I produce a shaving implement wherein the motor shaft is provided with two outer end portions, each adapted to engage a portion of an element for operating, simultaneously, the actuating sections, thereby distributing the motor-power evenly upon the motor-shaft and preventing eccentric strain upon such motor shaft; thus prolonging the life and usefulness of the instrument. Furthermore, to enable such simultaneous operation of the two end portions of the motor shaft, I provided such end portions with engagement-means located at varying degrees, thus preventing locking (of movements) of the parts during operation.

It will thus be seen that an object of the present invention is the provision of a shaving implement having a motor secured to a receptacle in a stationary non-movable manner, wherein the motor is provided with a shaft having two outwardly extending end portions and wherein the receptacle is provided with a shaft located parallel with the motor shaft and having two outwardly extending end portions, and wherein each of such end portions is provided with a disk having engagement means thereon and wherein connectable elements are connected to the said engagement means at varying degrees whereby the rotational movements of the motor shaft will rotate the shaft within the receptacle for operating the actuating section to cause the shaving units to be operated for shaving purposes.

Another object of this invention is the provision of a shaving implement wherein the motor may be positioned within the handle-portion and be held therein without the use of screw-elements.

A further object of this invention is the provision of a shaving implement wherein the individual shaving units may be secured into position without the use of screw-elements or tools and be removed therefrom without the use of tools or screw-elements.

2

Still another object of this invention is the provision of a shaving implement having a recessed portion at the outer face of the handle section shaped in a manner providing gripping means for the user's hand while shaving.

5 It is a further object of this invention to provide an electric shaver comprising an improved mechanism disposed in a housing which can be easily held in the hand in a convenient manner for shaving purposes.

A still further object of this invention is the provision 10 of a new and improved electrically operated shaving implement wherein the component parts can be readily assembled, and wherein the shaver is of sturdy and fool-proof construction having a trouble-free life many times that of similar implements available, and which is relatively inexpensive to manufacture.

The variety of possible application of my novel construction in connection with different types of shaving implements, as hereinabove indicated, is so prolific that for 15 the purpose of illustrating the invention the specific embodiment of my invention in its application to a shaving implement exhibiting the greatest difficulties has been selected. Such shaving implement is one which necessarily must conform most rigidly to the contours of the portion to be shaved and one which has the field of greatest possible commercial use. For this purpose I have selected for illustration of my novel construction, a shaving implement constituting a multiple-head electrically operated shaver, so that the principles of construction may be best illustrated in a shaving implement known as a 20 multiple-head electric shaver.

For a fuller understanding of the nature and objects of the invention, reference is had to the following detailed description in connection with the accompanying drawings, in which:

30 35 Fig. 1 is a perspective view of my shaving implement with the assembled shearing section in an hinged-open position showing the actuating-structure being carried by the shearing section, also showing the rotatable shaft located within the receptacle;

40 Fig. 2 is a view showing my improved inner mechanism located within the handle of my shaving implement, showing the motor being secured to the receptacle and having the motor shaft and the shaft within the receptacle in proper alignment with each other, and having the connectable elements engaging the outer end portions of such shafts in a varying degree for preventing locking of 45 the parts during shaving operation;

50 Fig. 3 is a view taken along the line 3—3 of Fig. 2, showing the position of one of the connectable elements at one of the side portions of my motor structure;

55 Fig. 4 is a view taken along the line 4—4 of Fig. 2, showing the position of the other of the connectable elements, located on the other side of the motor, at a varying degree;

55 Fig. 5 is a perspective view of my receptacle carrying the shaft therein;

Fig. 6 is a perspective view of my hingeable carrier;

Fig. 7 is a perspective view of the structure of my actuating section;

60 Fig. 8 is an enlarged view showing the manner in which my actuating section is carried by the carrier;

Fig. 9 is a view taken along line 9—9 of Fig. 8, showing the pivotal movements of the actuating section for operating the shaving units for shaving purposes;

65 Fig. 10 is a view, partly broken away, showing the position of the spring elements connecting the carrier to the receptacle and simultaneously therewith providing spring tension for holding such carrier in an hinged-open position;

70 Fig. 11 is a view taken along the line 11—11 of Fig. 10 showing the tensioning position of the spring element;

Fig. 12 is a view showing the connecting element for operating the shearing section for shaving purposes;

Fig. 13 is a view showing the locking structure of my shaving implement;

Fig. 14 is a view showing the connection between the 5 slidable element and the locking structure;

Fig. 15 is an enlarged perspective view showing the structure of the handle-casing;

Fig. 16 is a view showing the receptacle-shaft in assembled form;

Fig. 17 is a view of the same shaft as shown in Fig. 16, being partly assembled in a manner to be placed into position within the receptacle.

Fig. 18 is a view showing the front face of the disk;

Fig. 19 is a view showing the structure of the end portions of each of the shafts for being positioned within the slot of the disk;

Fig. 20 is a perspective view of my assembled shaving unit showing the under-structure thereof;

Fig. 21 is an enlarged modified perspective view of the 20 base portion of the inner movable cutter member of my shaving unit;

Fig. 22 is a modified view of the portion forming the stationary cutter member of my shaving unit;

Fig. 23 is a face-view of one of the elements forming the base portion of the stationary cutter member;

Fig. 24 is a cross-sectional view taken along the line 24—24 of Fig. 22;

Fig. 25 is a view showing the base portion of my modified stationary cutter member in assembled form;

Fig. 26 is a perspective view of a spring-plate;

Fig. 27 is a view showing the manner of positioning the spring-plate within the slotted portions of the movable cutter member shown in Fig. 21;

Fig. 28 is a view showing the spring-plate fully positioned within the slotted portions of the movable cutter member;

Fig. 29 is an assembled view of my modified shaving unit, partly broken away, showing the spring-plate being tensioned for urging the upper portion of the inner movable cutter towards the upper portion of the stationary cutter for frictional engagement therewith to effect a shearing action therebetween for shaving purposes,

Fig. 30 is a perspective view of the under-face of the carrier showing the manner in which the individual shaving units are secured thereto;

Fig. 31 is a view showing precisely the manner in which my shaving unit is held in position upon the carrier for shaving purposes;

Fig. 32 is a view showing a modified combination of the inner movable cutter member and spring-plate; and

Fig. 33 is a view showing the individual shaving units positioned in a manner having their shearing faces located at varying degrees.

I am showing the figures herein for illustrative purposes, for a better understanding of my invention, to be able to properly describe the herein invention, and not for limitation purposes.

Referring more particularly to the drawing, in which similar reference characters identify similar parts in the several views, in my novel shaving implement.

Arrow A indicates the handle structure of my shaving implement and arrow B indicates my assembled shearing section of my shaving implement.

Numeral 5 indicates the handle-casing for housing 65 therein the motor N, and arrow E indicates the hingeable carrier forming an assembled removable or hingeable shearing section carrying the individual shaving units d and the actuating structure 4 (Fig. 1).

The motor N is provided with a shaft 7 having the end portions thereof extending outwardly of such motor; one of such end portions is provided with a right-hand disk R and the other of such end portions is provided with a left-hand disk L (Figs. 2, 3 and 4) for a purpose which will be hereinafter explained.

The shearing structure indicated by arrow B comprises a receptacle 11 having a non-perforated floor 12 (Figs. 1 and 5), and side-wall portions 16 terminating into flanged-wall portions W and W', and is also provided with two upwardly extending facing side wall portions 18 and 19 each having a rear grooved or slotted end portion 21, for a purpose which will be hereinafter explained.

The under-face of the receptacle 11 is provided with two spaced apart downwardly extending wall portions 14 for having the upper portion of the motor N placed therebetween and secured thereto by suitable means, for example, rivets or screw-elements 15, in a manner preventing lateral movements therebetween (see Fig. 2).

A shaft 7' (Fig. 17) is provided at one of its end portions with a disk R' secured thereto in a non-movable manner; for example, the end portion of such shaft 7' is shaped to provide a flat portion 28 adapted to be positioned tightly within the opening 29 of the disk R' (Fig. 18), or be secured thereto by means of solder, or such flat portion may be riveted over or spread within the opening 29 for example as shown at R''. A washer 24 having a flanged portion 25 is then placed loosely over such shaft 7' and positioned against the inner face of the disk R'. A circular-shaped element 26 having an eccentric opening is then placed over the shaft 7' and positioned at about the center portion of such shaft 7' and secured thereto by suitable means; for example, friction-fit; or such element 26 may be an integral portion of the shaft 7'; the object of this element 26 is to provide the shaft 7' with a centrally located eccentric portion 26' for a purpose which will be hereinafter explained.

This shaft 7' is then placed through an opening 17 in one of the wall portions 16 carrying the eccentric portion 26' into the receptacle 11; the washer 24 is then placed frictionally into such opening 17 having its flange portion 25 overlying and covering the joint therebetween. A second washer, 27, similar in structure to the washer 24, is then placed into the opening of the opposite wall portion 16; the flat-shaped section 28 of the end portion 30 is then placed loosely through the opening of such washer 27 and then in a frictional manner into the opening 29 of the disk L' and secured thereto in the same manner as indicated by the numeral R''.

The disks R and R' are each provided with suitable fastening means for example pins P and P' adapted to be positioned through openings 35 and 35' located at the end portions of the bar-element C for holding such disks R and R' in a certain parallel position with respect to each other, for example, in a manner as shown in Fig. 3. The disks L and L' are each likewise provided with similar fastening means for example such as pins P1 and P2 for holding the bar-element D secured thereto.

It should be noted, that while the pins P and P' and the bridgeable bar-element C are located in a certain position, the pins P1 and P2 and the bridgeable bar element D are located in a varying or different position, that is, at a different degree; for example as shown in Fig. 4 (also see Fig. 2). Thus, while the motor shaft 7 is being rotated neither one of the bar-elements, C or D, will lock and cease to operate; instead, each one of the bar-elements will rotate its upper disk and cause the upper disk on the other end portion of the shaft 7' to move the other of the bar elements out of locking position thereby assuring continuous operation of the implement while shaving.

This type of structure is a very important feature of my herein invention. For clarification purposes I desire to point out the following: In the present type of electrically operated shavers only one end portion of the rotatable motor shaft is employed to operate the actuating structure for operating the shaving units for shaving purpose; this form of structure places an eccentric strain upon such motor-shaft during operation, it prevents proper precisional rotatable movements of such shaft

within its seat, it burdens the motor with excessive strain thereby shortening the life of such motor.

It is thus evident that my present invention, wherein both end portions of the motor shaft are connected to two end portions of an upper shaft for having a portion thereof operate, centrally, an actuating structure, is a desirable contribution to the art of making electrically operated shaving implements; it reduces motor-strain to a minimum thereby prolonging the life of the instrument and greatly improving the service thereof.

The carrier indicated by arrow E comprises a base portion 41 having two bifurcated or slotted sections 42 and 43. These sections are each shaped to provide spaced projections or ridges 46 and 47 separated by grooved sections 44 and 45. This carrier E is also provided with wall portions 48 and 49 and with a through opening 50 and also with two inwardly projecting floor portions 51 and 52 each terminating into a downwardly projecting extension 53 and 54 having openings 55. The wall portion 48 is provided with a rib section 56 having hook-portions 57; and the wall portion 49 is provided with a rear-extending section 58 having slotted pins 59 and 59' each having a shoulder portion 59" for a purpose which will be hereinafter explained (Figs. 1 and 6).

The individual shaving units d are each provided with undercut hook portions d1 and d2. These units are placed upon the sections 42 and 43 (Figs. 6, 20 and 30) having their neck portions d3 and d4 positioned adjacent the grooved sections 44 and 45 and being moved thereto in a manner whereby while the base portion or underface d5, of each shaving unit d, engages the upper face 49 of the sections 42 and 43, the hook portions d1 and d2 will engage frictionally the under-faces of the ridges 46 and 47 (Fig. 30) and hold its respective shaving unit secured in desired position.

The actuating structure 4 comprises a bifurcated or slotted base portion F (Fig. 7) having a neck portion F' which is provided with an opening F''. The neck portion F' is provided with a bridge section F1 having stem portions F2 each provided with sidewardly-extending circular-shaped pins 3, for a purpose which will be hereinafter explained.

This actuating structure 4 is placed between the two downwardly projecting extensions 53 and 54, in a manner whereby the opening F'' is located in proper alignment with the openings 55, having a pivot, pin or screw-element F3 positioned therethrough permitting pivotal movements of such actuating structure 4 in either directions (Fig. 9). It may be noted that the floor portions 51 and 52 are each of such a size in width whereby the side portions thereof will engage and limit the side movements of the actuating structure 4, as shown by dotted lines F4 and F4' engaging the floor portion 51, see numerals 51' and 51'', thus such actuating structure 4 will always be held in desired position by the carrier E (Figs. 1, 8 and 9).

The slotted pins 59 and 59' are each provided with a circular-shaped spring member S positioned thereover. These spring members S are each provided with an angularly disposed end portion S' (positioned within the slots S'' of such slotted pins 59 and 59') and with a coiled or looped end portion S1 (Figs. 10 and 11).

The connection of the carrier E to the receptacle 11 is, in accordance with my invention, a very simple and easy operation; placing the shoulder portions 59" of the carrier E into position within the grooved end portions 21 of the receptacle 11 will place the slotted pins 59, including the spring members S, into the spacious hollow section 21 (Fig. 10); this will place the coiled end portions S1 into position to be hooked on to the shoulder portions S2 and be held safely thereon by the head sections S3.

When the carrier E is placed upon the receptacle 11 it will be found that the coiled end portion S1 is located in a position remote from the shoulder portion S2 of the receptacle 11 (Fig. 5), for example as indicated by

the dotted lines S4 (Fig. 11); bringing such end portion S1 into position and connecting same to the shoulder portion S2 will cause such spring member S to provide spring tension and urge the angularly disposed end portion S' to move the carrier E (carrying the shaving units d and the actuating structure 4) into a hinged-open non-shaving position, disconnecting such actuating structure 4 from the shaft 7', for example, as shown in Fig. 1.

Placing the carrier E back into normal shaving position 10 will cause the hook portions 57 to enter the openings 62, of the wall portion W, and become interlocked, underneath such wall portion W, by having the slidible elements 63 placed into the grooved sections 64 and engage frictionally such hook portions 57 (Figs. 1, 5 and 13). 15 Thus such carrier E may be held in desired position for shaving purposes.

My above-mentioned slidible elements 63 may be constructed in any suitable manner; but for illustrative purposes I am showing such slidible structure comprising 20 a base portion 65 carrying angularly disposed elements 63 (Figs. 13, 14 and 15). The wall portion 61 of the handle casing 5 is provided with an opening or slot 61' of suitable shape and size. The slidible locking gauge indicated by arrow V (Fig. 1 and 14) comprises 25 an element 66 positioned within the slot 61'; this element 66 is of a size adaptable to slide within the slot 61', for the purpose of carrying the base portion 65 (to which it is secured by suitable pins or screw-elements 67) towards either direction sidewardly of the handle 5. For 30 example; moving the outer section 66' of the element 66 towards the side end portion 5'' will cause such element 66 to carry the base portion 65 towards each side portion 5'' and move the slidible elements 63 out of the grooved sections 64 (away from the hook portions 57), 35 thereby enabling the spring tension of the spring S to urge the carrier E into a hinged-open position as shown in Fig. 1; whereas, moving such outer section 66' towards the center portion of the handle, as indicated by arrow 3a (after the carrier E has been moved back into normal 40 shaving position), will cause the base portion 65 to carry the slidible elements 63 into the grooved sections 64 for engaging the hook portions 57 to hold such carrier E in locked position for shaving purposes.

The outer section 66', of the element 66, is of a size 45 larger than that of the slot or opening 61'; for example, it is provided with extending flange portions 66'' of a size and shape adapted to cover such slot 66' from view regardless of the location of the locking gauge V.

To facilitate the locking operation, I have provided the 50 hook portions 57 with reduced or tapered end portions 57a, serving as guiding means to facilitate the entering movement of the slidible elements 63 into the grooved sections 64.

The under-face d5 of the shaving unit d (Fig. 20) is 55 provided with a centrally located opening d6, for having one of the stem portions F2 positioned therein to engage the inner movable shearing member d8; to operate same for shaving purposes.

My shaving unit illustrated in Figs. 21-29 and 31 is 60 constructed upon an entirely new principle; this structure is practical, useful and economical to be manufactured. This unit comprises an outer stationary shear-member M and an inner movable shear-member M' (Fig. 29).

The stationary shear-member M comprises a thin 65 metallic sheet-portion M1, perforated centrally thereof, having two of its side portions secured to elements M2 (Fig. 22).

This element M2 may be made of any suitable material, but for illustrative purposes I am showing such 70 element M2 constituting a metallic sheet-form, stamped or shaped in a manner for example as shown in Fig. 23, and secured to the end portion M'' of the sheet-portion M1 in the following manner.

One of the end portions M'', of the sheet-portion M1, 75 is positioned upon one of the elements M2, having the

flange section M3 turn or bend over such end portion M2' as shown at M3' and clamped thereto. If desired, solder, welding-process or other means may be utilized to secure such end portion M'' to its seat. The same process is employed with respect to the second or opposite end portion M'' and the other element M2 (Figs. 22-24).

The sheet portion M1 is then bent into desired shape and the end portions M4 of the elements M2 are then shaped into desired form partly inclined as at M4' (see Figs. 25 and 31) and connected to each other by suitable means in any desirable manner; for example, as shown at M5 wherein the end portions M4 are connected to each other by spot-welding process, thus completing the construction of my new stationary shear member M.

The inner movable shear member M' comprises two spaced apart wall portions 1a each having an inwardly-located wall-section 1b. The wall portions 1a are connected to each other by a perforated bridge-section 1a1. The front wall portions 1b' are each provided with a grooved or slotted section 1a, and the rear end portions 1b'' are each provided with a grooved or slotted section 1a'' of a size double the length of that of the grooved sections 1a'. These wall portions 1b are each provided with a centrally located slot 1d and with inclined edge portions 1d' and 1d'' for a purpose which will be hereinafter explained (Fig. 21).

A spring plate 71, having at one of its end portion a pair of flat flange sections 72, is at the other of its end portion provided with a semi-circular-shaped section 73. This spring plate 71 is secured to the inner movable shear member M' in the following manner. The flange sections 72 are placed into the slots 1a'' and moved forward to an extent whereby the section 73 is located in front of the grooved sections 1a' (Fig. 27); the flange portions 73' are then placed into the slots 1a' and moved thereinto to an extent whereby the flange sections 72 will be located within the slots 1a'' adjacent to the outer end portions thereof (Fig. 28); the semi-circular end portions 73' will fit tightly within the slots 1a' and thus hold the flat-spring 71 secured in its position (Fig. 29).

Such assembled inner movable shear member M' is placed into the stationary shear member M before the end portions M4 are connected to each other thus the stationary shear member and the inner movable shear member form an assembled shaving unit.

It should be noted that the center portion of the spring plate 71 fits loosely between the two wall portions 1b, and that the two flange sections 72 fit loosely within the grooved sections or slots 1a'' for a purpose which will be hereinafter explained.

The sections 2 (Figs. 22 and 23) when connected to each other as shown in Fig. 31 form a neck portion d3' similar to the neck portion d3 as shown in Fig. 20, and the end portions M4 form hook portions d3' similar to the hook portions d1 as shown in such Fig. 20. These hook portions d1' may be secured to the ridges 46 of the carrier E in the same manner as are the hook portions d1; as clearly shown in Fig. 31. For clarification purposes I am showing space between the connecting portions; whereas, in reality, such connections are made in a frictional manner.

The thickness of the individual stem portion F2 is of such a size adapted to fit loosely between the two wall portions 1b, and the pins 3 are of a size adapted to fit loosely within the grooved section or slot 1d; so that when the assembled shear unit indicated by arrow K (Fig. 29) is placed in shaving position upon the carrier E, the pin portions 3 will slide upon the slanted edge portions 1d' or 1d'', of the wall portions 1b, until such pins 3 will slide into the slots 1d in which case the upper portion 3a of the stem F2 will press against the center portion of the flat-spring 71, causing the flange sections 72 to move within the slots 1a'' to an extent permitting such spring 71 to flex (as indicated by the dotted lines

5 3b) and provide spring-tension for urging the perforated bridge section 1a1, of the movable shear member M', into frictional engagement with the perforated sheet portion M1 of stationary shear member M for shaving purposes.

The pins 3 may be made in a manner as shown in Fig. 7, wherein such pins 3 are located below the upper portion 3a; but, if desired, such pins 3 may be located on top of the stem portion F2, for example, as shown in Fig. 8. The disclosures herein are for illustrative purposes only and not for limitation purposes.

If desired, the portion 73 of the spring 71 may be shaped in a flat manner, and the slot 1a' may be of a size wherein such portion 73 may be positioned therein in a frictional manner and thus be held secured in desired position. Or other means, for example welding-process, may be utilized for holding such flat-spring 71 in desired operable position for shaving purposes.

The operable action for moving the inner movable shear member M' is concentrated upon the pin portions 20 3 located within the slots 1d of such movable shear member, but there is no strain upon the spring 71 for displacing same from its position within the slots 1a' or 1a''.

If desired, the structure of the inner movable shear member may be modified; for example, to an extent as 25 shown in Fig. 32. Wherein the inner movable shear member indicated by arrow J, comprises a perforated flat-shaped metallic element 81 having flange portions 82 located at a lower level than that of the upper face of the metallic element 81. A yieldable structure 83, comprising flange portions 84 having angularly disposed wall portions 85 shaped to provide slanting wall portions 86, terminating into a centrally located recessed or semi-circular shaped portion 87, is secured to the metallic element 81 by any suitable means; for example, welding process or rivets 88 uniting or connecting the flange portion 82 with the flange portions 84. This structure may be positioned within the stationary shear member M forming a completed shaving unit.

In this form of structure the pin portions 3 of the actuating structure 4 may be eliminated. The top portions 3a may be positioned within the recessed portion 87, and press the yieldable structure towards the element 81, urging such element 81 towards frictional engagement with the shearing face of the shear member M; and simultaneously therewith move such movable shear member towards either one of the end portions of the stationary shear member M, as indicated by the dotted lines 3d, (Fig. 29) for shaving purposes.

From the above it is clear that the motor N and the receptacle 11 and the carrier E including the shaving units d and the actuating structure 4 are all united into an assembled unitary structure. This unitary structure can be placed into the handle casing 5 as an assembled unit and be removed therefrom as an assembled unit. For example; the handle casing 5 is provided with a rear wall portion 61 and with side wall portions 91 and with a floor portion 92 (Fig. 15). The side wall portions 91 are each provided with an inwardly disposed channel or grooved section 93 of a size adapted to hold therein the side portions 18 and 19 of the receptacle 11, as shown at numeral 90 Figs. 3 and 4.

The receptacle 11 is of a size shorter (or smaller) than the size between the wall portions 18 and 19, and is held in a non-movable position within the handle 5 by the inwardly disposed extending portions 94.

The channel portions 93 are each of such a size whereby the slotted pins 59 and 59' and the spring members S and also the head sections S3 may be housed therein when the wall portions 18 and 19 are located therein.

This assembled unitary structure may be placed within the handle 5 by sliding the wall portions 18 and 19 into their respective channel section 93 of such handle 5, and may be removed therefrom by sliding such wall portions 18 and 19 outwardly of such channel sections 93.

My handle casing 5 may be constructed in any suitable

manner. For example, formed of two sections, or provided with a cover, or in a cup-shaped style. For illustrative purposes I am showing my handle casing provided with a cover 5' (Fig. 1) secured to the casing 5 by screw-elements 99" positioned within the openings 99'.

The floor portion 92 is provided with an opening 95 and the motor N is provided with lugs or pins 95' (Figs. 4 and 15), for the purpose of connecting a cable-cord 95" thereto for operable purposes; this cable-cord 95" is provided with a plug 95a for connection with an electrical outlet, to provide means for operating the shaving implement. The handle 5 is provided with a starter 91' for starting the motor N for operable purposes. Removing the cable-cord 95" from the pins 95' will stop the operation of the motor N (Fig. 1).

The upper wall portions 96 are each provided with an outwardly lined or slantingly disposed inner face 96', that is, the upper portions of each of the faces 96' (which face each other) are spaced further apart than are the lower portions thereof (Figs. 3 and 4). The shaving units d are each shaped in a manner whereby their inclined or obliqued end portion 97 will fit closely to such outwardly lined faces 96', thus forming or providing a close connection between the shaving units and their respective facing wall portions 96'; preventing the escape of sheared hair and minimizing rattling of the shearing units while shaving.

If desired, the three individual shaving units d may be arranged in a manner whereby the shearing face of the center unit df may be situated at a lower level than that of the side units df' and df" (Fig. 33), thereby providing an enlarged shearing area for shaving purposes.

The present type of electric shavers are so constructed that they frequently slip out of the user's hand while shaving, causing damage thereto. To prevent such occurrences, I provided my shaving implement with a suitably located recessed or depressed portion 99, for example, at the side portions thereof (see Figs. 1, 3, 4 and 15), of a shape whereby the user may engage such depressed portion with his fingers and hold such implement safely in his hand, thus minimizing the possibilities of the shaving implement slipping out of the user's hand, preserving the precisionally-built mechanical structure of such shaving implements and the intactness thereof, thereby prolonging the life and usefulness of the shaving implement.

From the above it is evident that my present invention teaches an entirely new form of structure in the art of making electrically operated shaving implements. The novel form, or manner, in which my shaving implement is constructed; the novel feature of having my receptacle carrying the motor and simultaneously therewith carrying the removable (or hingeable) shearing section and also carrying the mechanism for operating such shearing section, and wherein such shearing section is carrying the shaving units and is also carrying the actuating structure for operating such shaving units; this novel form of structure wherein the receptacle is carrying the entire mechanism, and in addition thereto, such receptacle is also provided with means whereby the entire assembled unitary structure may be positioned into the handle casing in a slidable manner as an assembled unit and be held therein without the aid of screw-elements, and may be removed from such handle casing as an assembled unit, is a very important contribution to the art of making electric shavers. The novel form of combination of parts, wherein the actuating structure (carried by the carrier) is operable while being in a centrally located position; and wherein both of the end portions of the rotatable shaft (for operating such actuating structure) are in operable connection with the end portions of the rotatable motor-shaft (thereby preventing or eliminating eccentric strain upon such motor-shaft), and are located or arranged in a varying position for the purpose of enabling the rotatable movements of such shafts, is a very important achievement in the art of constructing electrically-operated shav-

ing implements. This form of structure presents improvements eliminating eccentric strain of the motor-shaft thereby minimizing strained frictional engagement, or rubbing, of motor parts; thus prolonging the usefulness of such parts and increase the life, or duration of usefulness, of such shaving implement. And also the fact that my shaving units are of a simplified form of structure, will greatly reduce the manufacturing cost of my units and thus of my shaving implement.

It will therefore be seen, that I have invented and perfected a shaving implement provided with an operable mechanism of a new and unique design and structure, a shaving implement which is practical and useful, economical to be manufactured and therefore of commercial value, and although I have shown certain preferred forms or illustrations in order to describe and explain the novelty of my invention, yet, by showing such structures, I do not, by any means, limit myself to these structures, nor to the terms used in describing same, as they are for illustrative purposes only. Various suggestions and changes of structure may be resorted to, and I desire it to be understood that I have same in mind when showing and describing this invention, and seek protection by Letters Patent. And although I have mentioned in describing this invention of what material certain parts may be made, how they may be formed, shaped or styled, and how they may be assembled, yet, I desire it to be understood, that this structure, or parts thereof, may be made of any suitable material; shaped, formed, styled or arranged in any suitable manner, and assembled in any suitable or convenient way, so that the parts may be easily taken apart, removed, cleaned, replaced and/or reassembled, and that various changes in detail may be resorted to without departing from the spirit of this invention.

I claim:

1. A shaving implement comprising a handle-casing housing a mechanism therein, said mechanism comprising a hair receptacle having a motor secured thereto and simultaneously therewith carrying an assembled shearing section, said receptacle having a rotatable shaft, said shaft having an eccentric portion, said assembled shearing section comprising a carrier carrying individual shaving units and also carrying in a pivotal manner an actuating structure for operating the said units, said actuating structure having a bifurcated base portion, the said eccentric portion located within the said bifurcated base portion, a bridgeable bar element, said motor having a rotatable shaft, said bridgeable bar element connecting the said motor shaft to the said first mentioned shaft in a bridgeable manner, means for providing the said motor with a source of power for rotating the said motor shaft to cause the said bar elements to rotate the said first mentioned shaft for having the said eccentric portion cause the said actuating structure to pivot and operate the said shaving units for shaving purposes, and means within the said handle-casing and the said receptacle for positioning the said mechanism in a slidble manner within the said handle-casing.

2. A shaving implement comprising a handle-casing housing a mechanism therein, said mechanism comprising a hair receptacle having a motor secured to the lower portion thereof and having a shearing section secured to the upper portion of such receptacle, said receptacle having a rotatable shaft, the end portions of said shaft extending outwardly of the side wall portions of such receptacle, said motor having a rotatable shaft, the end portions of said motor shaft extending outwardly of the side portions of such motor, bridgeable bar elements, one of said bar elements connecting one of the end portions of the said motor shaft to one of the end portion of the said receptacle shaft and another of said bar elements connecting the other of the end portions of the said motor shaft to the other of the end portions of said receptacle shaft at a varying degree, said receptacle shaft having an eccentric portion located within the said re-

ceptacle, the said shearing section comprising a carrier carrying a plurality of completed individual shaving units and thereunder carrying in a pivotal manner an actuating structure for operating such individual shaving units, said actuating structure having a bifurcated base portion, the said eccentric portion of the said shaft engaging the said bifurcated base portion for hinging the said actuating structure to operate the said shaving units for shaving purposes, the said shaving units situated outwardly of the said handle-casing for having the shear-faces thereof adapted to engage the user's face for shaving purposes, and means for operating the said implement.

3. In a shaving implement, a handle-casing, an assembled unitary structure comprising a shearing section having a completely assembled shaving unit and a mechanism for operating such shaving unit, said mechanism comprising a motor having a rotatable shaft, said rotatable shaft having end portions extending outwardly at two of the side portions of said motor, said shearing section having a rotatable shaft, said last mentioned shaft having end portions extending outwardly at two of the side portions of said shearing section and located in alignment with the end portions of the said first mentioned shaft, two bridgeable bar elements, one of said bar elements positioned at one of the side portions of the said assembled unitary structure having its end portions secured to the aligned end portions of the said two shafts and the other of said bar elements positioned at the other side portion of the said unitary structure having its end portions secured to the other aligned end portions of the said two shafts at a varying degree for operating the said mechanism to cause the operation of the said shaving unit for shaving purposes.

4. A shaving unit for a shearing section of a shaving implement, said shaving unit comprising a stationary shear member having a base portion and an inner movable shear member, said stationary shear member comprising a perforated flat metallic sheet element, two elements each having a bend-over flange section, one of said two elements covering one of the end portions of the said sheet element and the other of the said two elements

covering the opposite end portion of such sheet element, said two flanged elements connected to each other providing the base portion of the said stationary shear member and shaping the said perforated sheet element to provide a stationary shear-face, the said inner movable shear member comprising a perforated section having two wall portions extending therefrom, the said two wall portions each provided with a centrally located slot and with inclined edge portions, the said two wall portions having slotted end sections for holding therein a spring element to provide spring-tension for having the said perforated section urged towards the said shear-face of the said stationary shear member, the said centrally located slots adapted to have a portion of an actuating structure positioned therein for moving the said inner movable shear member within the said stationary shear member and to flex the said spring element to provide the said spring tension.
